Des. No. 1424

5-28-1861

C. W. COOKE, OF WATERLOO, N. Y.

Letters Patent for a Design, No. 1429, dated May 28, 1861.

SPECIFICATION.

TO ALL WHOM IT MAY CONCERN:

Be it known, that I, C. W. COOKE, of Waterloo, in the county of Seneca, and State of New York, have produced a new and ornamented design for Balmoral Skirts; and I do hereby declare that the following is a full, clear, and exact description of the same, reference being had to the accompanying drawing, making a part of this specification, in which—

Figure 1 represents a perspective view of my skirt.

Similar letters of reference indicate corresponding parts.

This design consists in a series of alternating stripes of gray or other pale color, and such of blue or other brilliant color and of increasing width from the first or highest stripe down to the last or lowest, said stripes of brilliant color being ornamented by one or more lines of some dark color drawn in their longitudinal centres, and separated from the stripes of pale color by borders of black or other dark color, the width of which is increased with the width of the stripe.

To enable others skilled in the art to fully understand my invention, I will proceed to describe it with reference to the drawing.

The lower end of the skirt A is ornamented by a series of stripes *a* of gray or some other pale color, which alternate with a series of stripes *b* of blue or some other brilliant color, said stripes of brilliant color being made of increasing width, as clearly shown in figure 1 of the drawing. The stripes *b* are separated from the stripes *a* by borders *c* of a black or other dark color, and one or more lines *d* are drawn through the longitudinal centres of each of the stripes *b*. These borders and centre line of the highest stripe being the narrowest and those of the lowest being the widest. By this form and disposition of the stripes the lower end of the skirt

Cooke's Design for a Balmoral Skirt.

produces a neat design, which by its regularity in the changes is agreeable to the eye.

Having thus fully described my invention what I claim as new and desire to secure by Letters Patent, is—

The stripes *a* of gray or other pale color alternating with stripes *b* of increasing width, and of blue or other brilliant color, and provided with borders *c* and centre lines *d*, as shown and described.
